UNITED STATES PATENT OFFICE.

SAMUEL S. SPEICHER, OF URBANA, INDIANA.

BROADCAST-SEEDING MACHINE.

SPECIFICATION forming part of Letters Patent No. 349,821, dated September 28, 1886.

Application filed August 22, 1885. Serial No. 175,091. (No model.)

To all whom it may concern:

Be it known that I, SAMUEL S. SPEICHER, a citizen of the United States, residing at Urbana, in the State of Indiana, have invented 5 certain new and useful Improvements in Hand Broadcast-Seeding Machines, of which the following is a specification, to wit:

This invention relates to hand broadcast-seeding machines; and it consists in the peculiar construction and arrangement of the same, substantially as will be hereinafter more fully set forth and claimed.

In order to enable others skilled in the art to which my invention appertains to make and 15 use the same, I will now proceed to describe its construction and operation, referring to the accompanying drawings, in which—

Figure 1 is a plan view of a broadcast seeder, such as I shall describe; and Figs. 2 and 3 are 20 perspective detail views of my invention.

A represents a seed-box, which is formed as shown or in any of the usual forms for such devices, and provided with a revolving distributing-wheel, A', having a spool, a, pivoted in 25 the main frame and an operating - bow, B, which is reciprocated transversely by the hand of the operator, and has a cord, b, which passes around the spool to operate the disk A'. In this construction I pass the bow through a 30 swiveled or pivoted guide, C, which turns freely as the bow is operated, and allows the bow to be operated equally well whether running at right angles to the seed-box or not. The guide may be made in various forms, as 35 shown in the drawings, Figs. 2 and 3. I prefer the form shown in Fig. 2, in which the guide consists of a piece of metal having upturned ends, through which the bow is passed and guided.

40 In Fig. 3 a small block of wood is represented as pivoted on the frame, and through which the bow runs. This is somewhat cheaper than the other form, but is not as preferable in practice. It will be seen that instead of the

hand moving in a right line in operating this 45 machine it may have a curved and easy swing from the shoulder, and thus operate with less strain and is not so liable to tire the person.

I shall when using this device place the springs D, which are always used on the bow, 50 at the guide, to the sides of which they are attached, and by this arrangement I am enabled to materially shorten the bow over the old way of placing these springs on the outer ends of the bow.

55 In this application I do not claim, broadly, any means whereby the bow is made to turn freely at different angles, as I have claimed the same broadly in my application Serial No. 131,428.

60 Having thus fully described my invention, what I claim as new, and desire to secure by Letters Patent, is—

1. In a hand broadcast seeder, a bow-guide pivoted upon the main frame, substantially as 65 and for the purpose set forth.

2. In a hand broadcast-seeder, a main frame provided with a distributing-disk and a bow-guide pivoted upon the main frame in proper relation thereto, in combination with an operating-bow passed through the swiveled guide and provided with a cord connected with the disk, substantially as and for the purpose set forth.

3. The bow-guide C, swiveled on the main 75 frame and formed of metal, having upturned ends perforated for the passage of the bow, substantially as shown and described.

4. The combination, with the swiveled bow-guide C, of the springs D, secured thereto on 80 each side, substantially as and for the purpose set forth.

In testimony whereof I affix my signature in presence of two witnesses.

SAMUEL S. SPEICHER.
